UNITED STATES PATENT OFFICE

159,739

MICROSCOPE LAMP

Howard C. Lindemann, Great Neck, N. Y.

Application October 12, 1949, Serial No. 5,449

Term of patent 14 years

(Cl. D57—1)

To all whom it may concern:

Be it known that I, Howard C. Lindemann, a citizen of the United States, residing in Great Neck, L. I., New York, have invented a new, original, and ornamental Design for a Microscope Lamp, of which the following is a specification, reference being had to the accompanying drawings, forming a part hereof.

Fig. 1 is a front and side perspective view of a microscope lamp embodying my design.

Fig. 2 is a rear and side perspective view thereof.

Fig. 3 is a front elevational view.

I claim:

The ornamental design for a microscope lamp, as shown.

HOWARD C. LINDEMANN.
